UNITED STATES PATENT OFFICE.

STEPHEN J. LANNIGAN, OF NEW YORK, N. Y.

BABY BED AND CRIB.

1,414,027.

Specification of Letters Patent. Patented Apr. 25, 1922.

Application filed August 17, 1920. Serial No. 404,052.

To all whom it may concern:

Be it known that I, STEPHEN J. LANNIGAN, a citizen of the United States, residing at 2170 Washington Ave., Bronx, New York, 5 have invented certain new and useful Improvements in Baby Beds and Cribs, of which the following is a clear, full, and exact description.

This invention relates to baby beds or cribs. The invention is particularly designed to be embodied in a baby crib adapted to be set up and carried in an automobile. Certain features of the invention, however, are not limited to cribs designed for this particular purpose, but may be applied to other kinds or classes of cribs.

The primary object of the invention is to provide a crib of the above class which will form a strong, rigid structure when set up for use and when not in use may be collapsed and packed away into a small space.

With this object in view the invention comprises the novel and improved features, constructions and combinations of parts 25 hereinafter described and particularly pointed out in the claims, the advantages of which will be readily understood and appreciated by those skilled in the art.

The invention will be clearly understood 30 from the accompanying drawings illustrating the invention in its preferred form and the following detailed description of the constructions therein shown.

In the drawings—

Fig. 1 is a view in side elevation of a 35 crib embodying the invention, showing the same set up in an automobile, the outline of the automobile body being indicated in dot-and-dash lines;

Fig. 2 is a sectional view of the crib taken substantially on the line 2—2 of Fig. 1;

Fig. 3 is a detail sectional view taken substantially on the line 3—3 of Fig. 1;

Fig. 4 is a detail sectional view taken substantially on the line 4—4 of Fig. 2; and

Fig. 5 is a detail view in side elevation illustrating one of the clamps by which the crib is secured to a support such as the back of the front seat of the automobile.

The crib illustrated in the drawing 50 comprises a collapsible stand preferably constructed of metal and a mattress support suspended on the stand. The crib stand includes a rectangular frame indicated at 2, to the end and side members of which is secured a web preferably consisting of a

suitable fabric for supporting a mattress or blanket 4. The frame 2 is arranged to be supported at its opposite end by end supports 6. These end supports are preferably each constructed in an A shape as clearly shown in Fig. 1, and the upper ends thereof are pivoted on the end members of the frame 2, the end supports having openings through which the end members of the frame pass. To hold the end supports from turning on the end members of the frame 2, thumb screws 8 are threaded into the end supports and are engaged with the end members of said frame.

To hold the end supports 6 in a predetermined spaced relation, brace rods 10 are mounted to turn on the cross-bars of the end supports and are adapted to be held from turning on said cross-bars by thumb screws 12 respectively threaded into the brace rods and engaging the cross-bars. The inner end of one of the brace rods 10 is provided with a tongue arranged to engage in a slot in the inner end of the other 80 brace rod and a thumb screw 14 is provided to connect the inner ends of the brace rods.

When set up in an automobile the crib stand may be secured in position by means of clamp brackets 16. As shown in the 85 drawing, these clamp brackets are attached to the back of the front seat of the automobile. The rear end of the horizontal arm of each clamp bracket is constructed to form one member of a clamp embracing one of 90 the side members of the rectangular frame 2. The other member of the clamp indicated at 18 is pivoted at 20 to the cooperating clamp member and is held in closed position by means of a thumb screw 22.

The crib is shown as provided with a canopy attached to the crib stand. This, however, is not essential, but the crib may be used without the canopy if desired.

The crib stand described above, when set 100 up for use, forms a strong, rigid structure capable of withstanding comparatively heavy lateral or endwise strains. When not in use, however, the stand may be readily collapsed and folded up compactly so that 105 it will occupy a relatively small space. In collapsing the stand, the thumb screws 8 and 12 are loosened, and the inner ends of the brace rods 10 are disconnected by removing the thumb screw 14. The brace rods 10 110 are then swung about the cross bars of the end supports 6 in the direction of the arrows

a, Fig. 2, to the outside of the end supports 6, until they rest against the upper ends of said supports and the end supports are swung inwardly about the end members of the 5 frame 2 as indicated by arrows 7 in said figure, one outside of the other, and are folded against the rectangular frame 2.

The canopy shown in the drawing comprises a collapsible canopy frame supported 10 on the thumb screws 8 and a canopy fabric covering said frame. The canopy frame comprises uprights 24, the lower ends of which are provided with openings through which the thumb screws 8 are passed, the 15 thumb screws preferably being threaded into the uprights. The upper ends of the uprights are connected by a ridge pole 26, over which the canopy fabric 27 is passed.

To the uprights 24 are secured cross bars 28, to the ends of which the canopy fabric is attached. The ends of the cross bars are preferably bored to receive plugs of wood or similar material indicated at 30, and the canopy fabric is attached to the ends of the 25 cross-bars by nails or screws 32 driven into said plugs. Cross-bars 28, as shown, are engaged in recesses in the uprights 24 and are held in place by thumb screws 34, preferably threaded into both the uprights and the cross 30 bars.

To enable the canopy to be more readily collapsed, the cross-bars 28 are preferably made in two parts, the inner end of one of which parts is provided with a tongue engaging 35 in a slot in the inner end of the other part of the cross-bar as shown clearly in Fig. 4. The parts of each of the cross-bars are held together by the thumb screw 34, which is 40 preferably threaded through the uprights 24 and through the inner ends of the parts of the cross bar as shown in this figure.

The canopy may be removed from the crib stand by removing the thumb screws 8 from the end supports 6. Then, upon removing 45 the thumb screws 34 from the cross bars 28, the parts of the cross bars may be separated and the cross bars with the canopy fabric may then be folded substantially into the plane of the ridge pole 26 and the uprights 24.

Having explained the nature and object of the invention, and having specifically described a device embodying the invention in its preferred form, what is claimed is:

5. 1. A baby crib having in combination a rectangular frame comprising side and end members, a web for supporting a mattress extending across said frame, end supports having cross bars and pivoted on the end 50 members of said frame to swing into positions adjacent said frame, adjustable means for securing the end supports from turning on said end members, brace rods pivoted on the cross bars of said end supports to swing 55 into positions adjacent said supports for

holding the end supports in predetermined spaced relation and adjustable means for securing the brace rods from turning on said cross bars.

2. A baby crib having in combination a 70 rectangular frame comprising side and end members, a web for supporting a mattress extending across said frame, end supports having cross bars and pivoted on the end members of said frame to swing into positions adjacent said frame, adjustable means for securing the end supports from turning on said end members, brace rods pivoted on the cross bars of said end supports to swing 75 into positions adjacent said supports for holding the end supports in predetermined spaced relation, adjustable means for securing the brace rods from turning on said cross bars and means for detachably securing the ends of the brace rods together. 80

3. A baby crib having in combination a frame, a web for supporting a mattress extending across said frame, end supports pivoted on said frame, a canopy frame, a canopy fabric secured to said canopy frame and common adjustable means for securing the end supports from turning relatively to said first frame and for detachably securing the canopy frame to the first frame. 90

4. A baby crib having in combination a 95 frame, a web for supporting a mattress extending across said frame, supports pivoted on opposed members of said frame to swing into positions adjacent said frame, brace rods pivoted on said supports, adjustable 100 means for securing said supports from turning on said frame, adjustable means for securing said brace rods from turning relatively to said supports and means for detachably securing the ends of the brace rods 105 together.

5. A baby crib having in combination a non-collapsible frame, a web for supporting a mattress extending across said frame, supports pivoted directly on to swing 110 about opposed members of said frame into positions adjacent said frame and adjustable means for securing the supports rigidly to said opposed members.

6. A baby crib having in combination a 115 supporting frame, a web for supporting a mattress extending across said frame, supports pivoted on opposed members of said frame to swing into positions adjacent said frame, adjustable means for securing said 120 supports rigidly to said opposed members, brace rods pivoted on said supports and adjustable means for securing said brace rods rigidly to said supports.

7. A baby crib having in combination a 125 frame, a mattress support carried by said frame, spaced supports pivoted to said frame upon axes substantially parallel with the plane of said frame to swing into positions adjacent the plane of said frame, brace rods 130

each pivoted at one end to one of said spaced supports to swing into a position adjacent to said support, and means for detachably securing the other ends of the brace rods in 5 position.

8. A baby crib having in combination a frame comprising longitudinal and transverse bars, a mattress support carried by said frame, spaced supports having cross 10 bars, and respectively pivoted on opposite bars of said frame to swing into positions adjacent to said frame, set screws threaded into said supports and engaging said bars to hold the supports from turning thereon, brace rods 15 pivoted on the cross bars of said supports to swing into positions adjacent to said supports, set screws threaded into said brace rods and engaging said cross bars to hold the brace rods from turning on said 20 cross bars.

9. A baby crib having in combination a frame comprising longitudinal and transverse bars, a mattress support carried by said frame, having cross bars and respectively spaced supports pivoted on opposite bars of 25 said frame to swing into positions adjacent to said frame, set screws threaded into said supports and engaging said bars to hold the supports from turning thereon, brace rods pivoted on the cross bars of said supports to 30 swing into positions adjacent to said supports, set screws threaded into said brace rods and engaging said cross bars to hold the brace rods from turning on said cross bars and means for detachably securing the 35 ends of the brace rods together.

Signed at New York city, this 10th day of August, 1920.

STEPHEN J. LANNIGAN.
